WEDDING CAKE ORNAMENT

Geza Dombi, 4060 Carlock Drive,
Boulder, Colo. 80303

Filed June 1, 1970, Ser. No. 23,217

Term of patent 14 years

Int. Cl. D11—02

U.S. Cl. D29—24

FIG. 1 is a front elevational view of a wedding cake ornament showing my new design, the side opposite thereto being a mirror image thereof;

FIG. 2 is a side elevational view; and

FIG. 3 is a top plan view.

I claim:

The ornamental design for a wedding cake ornament, substantially as shown and described.
